R. V. MORSE

ROAD SWITCH FOR ELECTRIC GARAGE DOORS

Filed April 25, 1925

FIG. 1.

FIG. 2

INVENTOR

Robert V. Morse

UNITED STATES PATENT OFFICE.

ROBERT V. MORSE, OF ITHACA, NEW YORK.

ROAD SWITCH FOR ELECTRIC GARAGE DOORS.

Application filed April 25, 1925. Serial No. 25,901.

This invention relates to electric switches, especially in relation to electric mechanisms for opening or closing garage doors without leaving one's automobile. The object of this 5 invention is to obtain a simple and serviceable type of switch which can be placed in the driveway leading to the garage, and which will operate satisfactorily over long periods of time in spite of the severe conditions,—involving dirt, rain and snow,—to which such a switch must necessarily be exposed. The switch is normally operated by the wheel of a car passing over it, which not only brings dirt and snow, but also exposes 10 the switch to certain driving forces from the power of the wheel which increase the difficulties of the problem. The object of the present invention is to solve this problem in a reliable and inexpensive manner, in order 15 to extend the field of such devices.

Referring now to the drawings, Fig. 1 is a transverse cross-section of one illustrative form of the device; and Fig. 2 is a cross-section at right angles to that shown in Fig. 20 1, taken thru the center of Fig. 1.

The mechanism as illustrated in Fig. 1 and Fig. 2 consists of a heavy box frame 1, ordinarily made of cast iron or some other strong and inexpensive material, two sides of 25 this frame 1 being rounded up toward the top, as shown in Fig. 2, while on the two other sides or ends, as shown in Fig. 1, the frame 1 does not ordinarily stand up so far, and is rounded so as to provide a pivot or 30 fulcrum point for the lid 2 which rests loosely thereon. In the particular form selected as an illustration there are a pair of these lids 2, similarly arranged, and pivoted at either end of the frame 1, though a larger 35 or smaller number of lids might be used.

The lids 2 are a loose fit in the frame 1, both between the sides as shown in Fig. 2, and over the ends as shown in Fig. 1.

This loose fit is an important factor in securing reliable operation under conditions of dirt, ice and snow, since when an obstruction 45 occurs the mechanism can give instead of bind, and the mechanism will then continue to operate under conditions where it would 50 jam if more rigid connections were used. The plates 2 are normally held in place by their weight, being generally rather thick and made of cast iron or some similar heavy material. The mechanism can be easily 55 inspected at any time by merely lifting off one of these plates 2 if desired.

To carry off rain and dirt a series of sloping roofs is employed, leading anything that may enter downward to the ground. For example, if rain falls on the form shown, 60 that which falls on the lids 2 will drain off sideways as will be evident from Fig. 1, and that which falls on the thick sides of the frame 1 shown in Fig. 2 will also drain off. The only place that rain can enter is thru 65 the crack between the two lids or between the lids and the sides of the frame. What small proportion of the downpour that falls directly on these cracks is carried downward to the comparatively large spaces within the 70 frame which are open to the ground.

Extending across the middle of the frame 1 is a cross-piece 4, which supports the electric push button 7 considerably above the level of the ground. The push button 7 is 75 connected to the electrical mechanism to be controlled by means of the leads 9. In order to positively operate the button 7 whenever a heavy pressure is applied to the lid 2, and at the same time to insure against any possibility of overloading the button 7 so as to 80 crush it, the following means is provided.

A spring 6, lying in a groove in the cross-piece 4, is looped around so as to have a pair of free ends which may bear upon the button 7; and the load of the lid 2 is applied to the spring 6 at a point 3 nearer the fulcrum or support of the spring, where the carrying capacity of the spring is greater. A slight motion at the point 3 means a large motion 85 of the tip of the spring where it bears on the button 7. Thus the button 7 is positively operated, and at the same time the pressure on the button is of a soft, yielding character,—being applied by the free end of the 90 flexible spring 6, so that the button cannot be damaged. In addition to this feature, any excessive movement of the lids 2 is prevented by their coming in contact with heavy 95 iron stops 8, which then take the direct load 100 and prevent the spring 6 from being overloaded.

The cross-piece 4 is provided with ridges 5 which keep the spring 6 in place, and drainage channels are cut thru these ridges 105 5 which drain off any water which may work in, and also provide openings for the electrical conductors 9. In addition a strip of thin sheet copper 10 is generally laid on top of the spring 6 but under the points 3, 110 forming the initial surface which anything coming thru the crack between the lids 2

will strike. This sheet of copper, being flexible, soon conforms itself to the adjacent elements, and effectively shields the spring 6 and elements below. In some cases another thin strip of copper 11 is laid loosely within the spring 6 between the button 7 and the free ends of the spring 6, thus protecting the button from the cutting effect of the impact of the spring tips, and at the same time affording added protection against rain and dirt.

The whole structure is sufficiently heavy so that it will not be knocked about, and it can be neatly secured in position in the driveway by pegs driven into the ground at the corners inside the frame 1, where they will be out of sight. The top of the structure projects sufficiently high above the ground to insure that a driver will feel a gentle bump when he runs on it, this feature facilitating the use of the switch in the dark. In operation the plate 2 is depressed by the weight of a wheel of a car, or other heavy load, and depresses the spring 6 which operates the electric switch 7 as described. When the car rolls off and the heavy load is removed, the spring 6 is sufficiently powerful to raise the lid 2 again, thus lifting the tip of the spring 6 from the push button 7 and opening the electric circuit. The spring 6 may be made sufficiently strong so that the device cannot be operated by the weight of dogs or children.

In case only one lid is used instead of two, it would of course preferably extend entirely across the frame 1, which would throw the spring and switch mechanism over to one side. In the foregoing specification one embodiment of the invention has been described by way of illustration. It will be understood however that the invention is not limited to the particular structure therein shown, but may have various modifications to adapt it to different installations, as will be apparent to those skilled in the art. The particular arrangement shown is merely one illustration; and the essential features and combinations which constitute the invention are embodied in the following 50 claims.

I claim:

1. In an electric switch mechanism, the combination of a frame rounded toward the top, a lid loosely jointed to the frame so that it may give rather than bind when obstructed, and by shifting laterally may relieve the pressure of an obstacle which would otherwise jam in a crack, an electric switch of the self-releasing type, and yielding spring means between the lid and the switch arranged so as to multiply the motion of the lid and operate the switch.

2. In an electric switch mechanism, the combination of a frame rounded toward the top, a lid loosely jointed to the frame so that

it may give rather than bind when obstructed and by shifting laterally may relieve the pressure of an obstacle which would otherwise jam in a crack, an electric switch of the self-releasing type, and a yielding spring means between the lid and the switch arranged so as to multiply the motion of the lid and operate the switch, and another point of support arranged to come in contact with the lid when it is fully depressed so as to prevent the spring from being overloaded.

3. In an electric switch mechanism, the combination of a frame, a lid jointed to said frame and lying between the side walls of said frame, there being sufficient clearance between the lid and said side walls so that the lid may give rather than bind in case of an obstruction in the crack between the lid and a side wall, openings in the frame for carrying off water that may fall in said crack, an electric switch of the self-releasing type, and yielding spring means between the lid and the switch arranged so as to multiply the motion of the lid and operate the switch.

4. In an electric switch mechanism, the combination of a frame, a lid loosely jointed to said frame, an electric switch of the self-releasing type, a member connected to said frame and arranged to support said switch so that its contact points will be at a level above the bottom of said frame, drainage channels from said member arranged to carry off any water that might fall upon said switch, yielding means between said lid and said switch arranged to operate said switch when the lid is depressed, and supplemental means for carrying the load on the lid when it has become excessive.

5. In an electric switch mechanism, the combination of a frame, a pair of lids pivotally mounted and loosely jointed near opposite ends of the frame and extending toward the middle, a spring arranged to support the free ends of the lids, a switch of the self-releasing type arranged to be operated by the depression of the lids, means for supporting said switch above the level of the bottom of the frame, said frame having openings by which any water that may fall on the switch will drain off to a lower level.

6. In an electric switch mechanism, the combination of a frame, a pair of lids pivotally mounted near opposite ends of the frame and extending toward the middle, the lids having grooves at their pivoted ends which fit over ridges of the frame forming a fulcrum about which the lids may oscillate, the lids being removable by lifting from the ridges and being held in place by their weight, a spring supporting the other end of the lids, limit stops to prevent the spring from being overloaded, a switch of the self-releasing type arranged to be operated by the deflection of the spring, and a shield ex-

tending over the switch but below the lids.

7. In an electric switch mechanism, the combination of a frame and a lid having a loose tongue and groove connection about which the lid may oscillate, the lid being removable by lifting from the tongue and groove connection and being held in place by its weight, a yielding member support-

ing said lid, a switch of the self-releasing type arranged to be operated by the depression of the lid by a superimposed load, and a limit stop arranged to limit the depression of the lid under load.

In witness whereof I have hereunto set my hand this 23d day of April, 1925.

ROBERT V. MORSE.
